UNITED STATES PATENT OFFICE.

WILLIAM W. HOFFMAN AND FRANCIS W. POWERS, OF WEST LAFAYETTE, INDIANA, ASSIGNORS TO ELECTRIC & STEAM RAILWAY SUPPLY COMPANY, OF LAFAYETTE, INDIANA.

TROLLEY CATCHER AND RETRIEVER.

SPECIFICATION forming part of Letters Patent No. 784,678, dated March 14, 1905.

Application filed September 23, 1904. Serial No. 225,655.

To all whom it may concern:

Be it known that we, WILLIAM W. HOFFMAN and FRANCIS W. POWERS, citizens of the United States, residing at West Lafayette, in the county of Tippecanoe and State of Indiana, have invented certain new and useful Improvements in Trolley Catchers and Retrievers; and we do hereby declare the following to be a full, clear, and exact description of the invention, such as will enable others skilled in the art to which it appertains to make and use the same.

This invention relates to improvements in trolley catchers and retrievers, the objects and advantages of which will more fully appear in the following specification, the particular features of novelty being succinctly pointed out in the claims.

To more fully understand the invention, reference is had to the accompanying drawings, illustrating the preferred construction and arrangement of the component elements of the device; in which the same letters indicate the same parts in the several views, and in which—

Figure 1 is a vertical section through the casing, the operating parts being shown in elevation with parts broken away to more clearly illustrate the internal mechanism. Fig. 2 is a central vertical transverse section looking to the left in Fig. 1. Fig. 3 is an end view of the tripping mechanism, the springs and housing being shown in section. Fig. 4 is a detail view, in side elevation, of the tripping device in its tripped position, a fragment of the disk only being shown. Fig. 5 is a similar view of the tripping mechanism with the detent-bar shifted to the right and secured in its lowermost position for converting the device into a catching mechanism only without the retrieving feature; and Fig. 6 is a view in elevation, on a reduced scale, of the support carried by the dashboard of the car to which the casing is detachably secured.

A is a cylindrical casing having its peripheral surface slotted, as at A^o, and provided with the internally and externally extending central boss A² on its rear wall, the front

portion of the casing being left open, if desirable, as illustrated in the drawings, but normally closed by the outer plate of a winding-drum hereinafter referred to.

B is a spindle rigidly supported at one end within said boss A² and at its other end is provided with suitable means for holding in position thereon the winding-drum referred to. For the purpose of illustration we have simply shown a washer or cap-plate B', secured to the outer end of the spindle by the screw b.

C is a sleeve revolvably mounted on the spindle B and provided with the disk D, having the annular rim D', on the inner face of which are formed the ratchet-teeth d.

The peripheral surface of the rim D' is provided on one side of its center with the longitudinally-curved lug E and rearwardly of said lug E, and disposed on the opposite side of the center of said rim is a second longitudinally-curved lug E', projecting in the opposite direction.

F is a coiled spring interposed between the sleeve C and the casing, which spring has a sufficient motive power to pull down the trolley-pole when brought into play against the tension of the springs ordinarily employed to hold the trolley-wheel in contact with the trolley-wire.

The winding-drum for the trolley-rope is loosely journaled on said sleeve C within the space formed between the disk D and the front of the casing, and this drum comprises the peripheral wall G, the central vertical partition G', and the side plates g g', the side plate g being adapted to substantially close the front of the casing, although a front plate may be employed, if desired.

H represents dogs pivoted to the outside face of the side plate g', which dogs are provided with the teeth h, disposed in alinement with the teeth d of the rim D', but normally held out of engagement therewith by the free ends of the springs h', secured at their other ends to suitable supports.

Within the space formed by the vertical partition G' and side plate g is a coiled motor-spring J, interposed between the winding-

drum and the sleeve C, which spring is sufficiently strong to normally rotate the winding-drum for keeping the trolley-rope I taut, but too weak to overcome the tension of the springs 5 normally holding the trolley-wheel in contact with the trolley-wire.

At the top of the casing A is secured in any suitable manner the housing K, being disposed over the slot A⁰ and adapted to contain 10 a tripping mechanism hereinafter described. This housing may be provided with a suitable handle K' for the purpose of portage and may form either a separable or integral part of the casing.

15 For the purpose of having ready access to the mechanism within the housing one or more of the walls thereof may be in the nature of a detachable plate, the front wall of the housing being thus shown detachable in 20 Fig. 2.

The tripping mechanism comprises the elongated detent-bar L, slotted, as at L⁰, and pivotally mounted within said housing on the pivot-screw L', supported by the side walls of 25 the casing and passing through said slot L⁰. Between the head of the screw L' and the detent-bar L is interposed a spring-pressed washer or friction-washer of any suitable construction and material. The object of the 30 friction-washer is to permit of the longitudinal movement of the detent-bar and at the same time retarding its movement to a certain extent, and this may be further regulated by the adjustment of a suitable spring adapted 35 to press the washer in position. In the drawings the washer is designated as M, engaged by a suitable spring m, adjustably secured to the casing by the screw m'.

40 The forward end of the detent-bar L is provided on its underneath edge with a tooth l and on its upper edge with the tooth l'.

N designates a weak spring secured at its rear end to the top of the housing and at its free end projecting beneath a pin n at the forward end of the detent-bar L and exerting an 45 upward pressure thereon.

O is a strong spring similarly secured at one end to the top of the housing and projecting forwardly and downwardly at its free 50 end above said detent-bar L, tensioned to press downwardly and adapted to normally rest at its free end on a ledge or stop o, carried by the housing. On the underneath face of this flat spring O is carried a block O', disposed 55 adjacent the tooth l' and forming a yielding stop for the forward end of the detent-bar.

P is a dog pivoted to the rear end of the detent-bar L and having its lower end normally projecting downwardly beneath the lower 60 edge of the detent-bar L in the path of the lug E', a coiled spring p, interposed between said dog P and a stop p', carried by the bar L, normally tending to hold said dog P in engagement with the stop p' for limiting the 65 rearward swing of the dog P.

In order to utilize the mechanism simply as a catcher for the trolley and not as a retriever, we have provided additional means. These means comprise the spring Q, located beneath the spring O and similarly secured at its rear 70 end to the top of the housing. The forward end of the spring Q is bent downwardly and outwardly, as at q'q, the bent portion q' forming a lip disposed beneath the block O' and immediately above the upper edge of the detent-bar L. This spring Q is tensioned to 75 press downwardly and is of a greater strength than the spring N, so that when released it will hold the detent-bar L in its lowermost position against the upward pressure of the 80 spring N.

R designates a spindle journaled in the rear wall of the housing, which may be suitably reinforced at this portion for the purpose, the inwardly-projecting end of the spindle having 85 a cut-away portion r, leaving the shank r' adapted to project beneath the strong spring Q at its bent end. The outer end of the spindle R is provided with an index finger or handle r², which will serve as a means for operating 90 the spindle R and indicating the position of the shank or extension R'. It is obvious in Figs. 1 to 4 that when the shank or extension r' is in its uppermost position the spring Q will be held in an inoperative position with 95 respect to the detent-bar; but when the spindle R is rotated to bring the shank or extension r' to its lowermost position the lip q' of the spring Q will press against the detent-bar L and hold the same rigidly in position with respect to 100 the disk D.

It is obvious that duplicate mechanism may be carried at each end of the cars; but in practical operation and for cheapness it is preferable that the casing and mechanism be of a 105 portable character. With this object in view we have shown a metal frame, preferably of the construction illustrated in Fig. 6, adapted to be secured to the dashboard of a car in any suitable manner. The metallic frame S in 110 the construction illustrated is of an oval form provided with an apertured portion s at its base for the reception of a lug a', carried at the bottom of the casing A, the upper end of the frame S being provided with a recess s', 115 adapted to register with the recessed portion t of a locking-button T and to receive a lug a², carried by the top of the casing opposite the lug a'.

A hook U is provided in any convenient 120 place to wrap the rope I around when desired.

When the parts are in the position shown at Figs. 1 and 2, the winding-drum is free to rotate in either direction and holds the trolley-rope taut; but the clutch-disk D is held against 125 rotation by the tooth l on the detent engaging the lug E. Should the trolley jump the wire, however, the pole springs upwardly with some little force and the winding-drum being rapidly rotated to the right the pivoted 130

dogs H are moved outwardly, and the teeth h thereon engaging the ratchet-teeth d of the clutch-disk jars the latter sufficiently to the right to release the tooth l from engagement with the lug E, the spring N then elevating the forward end of the detent-bar out of engagement with the clutch-disk. The clutch-disk being thus released will be revolved to the left by its actuating-spring and being locked to the winding-drum by the interposed dogs H will rotate the winding-drum also and retrieve the trolley-pole.

While the clutch-disk is being rotated to the left the lower end of the pawl P will ride over the curved upper face of the lug E', the dog being free to swing to the left against the tension of the spring p.

In resetting the parts the trolley-rope is pulled upwardly, (the springs controlling the trolley-pole assisting the operation,) and the dogs H being retained in engagement with the clutch-disk by the tendency of the drum and disk to rotate in opposite directions the disk also is rotated to the right, winding up its motor-spring.

During the disk's rotation to the right the lug E' engages the lower end of the dog P, which initially swings the forward end of the detent-bar downwardly around its pivot L', and the continued rotation of the disks moves the detent-bar bodily to the right, the forward end of same resting beneath and held down in position by the resiliently-mounted block O'. (See Fig. 5.) During continued rotation of the disk to the right the forward end of the detent-bar rides over the curved upper face of the lug E, the upward rise being allowed for by the resiliency of the spring O, carrying the block O'.

When the rope has been sufficiently paid off of the drum and the lug E being to the right of the tooth l, the manual pull on the rope is released and the lug E engages the tooth l and moves the detent-bar bodily to the left, the parts again assuming substantially the position shown in Fig. 1, when upon a slight downward pull on the trolley-rope the pivoted dogs H will be forced out of engagement with the ratchet-teeth d by the springs h', and the mechanism is again reset.

When it is desired to use the apparatus as a catcher only, it is obvious from the foregoing description that by turning the index finger or handle ² to the left from the position indicated in dotted lines, Fig. 1, the spring Q will be released from its inoperative position and will press downwardly on the detent-bar L, as shown at Fig. 5. In this position it is manifest that the detent-bar will not be released from the disk should the trolley leave the wire, as the spring Q is stronger than the spring N. The locking-dogs H will, however, coöperate as heretofore with the disk for arresting the upward movement of the pole.

We do not limit ourselves to the exact de-

tails shown and described, the same simply showing the preferred embodiment of the invention, and many modifications might be made without departing from the spirit of the invention, and we wish it particularly understood that although we have for the purpose of clearness of description only referred to one lug E and E' on the clutch-disk a plurality of such lugs may be disposed around the periphery of the disk.

75

What we claim, however, is—

1. The combination with the winding-drum, disk, actuating means and automatic interlocking means therefor, of non-alined lugs carried by said disk, a pivoted detent-bar provided with forward and rear projections adapted to ride over said lugs in one direction of rotation of said disk and to engage same in the opposite direction of rotation, and means normally exerting upward pressure on the detent-bar.

80

2. The combination with the winding-drum, disk, actuating means and automatic interlocking means therefor, of non-alined fixed lugs carried by said disk, a pivoted detent-bar provided with forward and rear projections adapted to ride over said lugs in one direction of rotation of said disk and to engage same in the opposite direction of rotation, and means normally exerting upward pressure on the detent-bar.

85

3. The combination with the winding-drum, disk, actuating means and automatic interlocking means therefor, of non-alined lugs formed integral with said disk, a pivoted detent-bar provided with forward and rear projections adapted to ride over said lugs in one direction of rotation of said disk and to engage same in the opposite direction of rotation, and means normally exerting upward pressure on the detent-bar.

90

4. The combination with the winding-drum, disk, actuating means and automatic interlocking means therefor, of non-alined lugs carried by said disk, said lugs being curved and tapering rearwardly and forming opposed abutment-faces, a pivoted detent-bar provided with forward and rear projections adapted to ride over said lugs in one direction of rotation of said disk and to engage same in the opposite direction of rotation, and means exerting upward pressure on the detent-bar.

100

5. The combination with a winding-drum, disk, actuating means and automatic interlocking means therefor, of non-alined lugs carried by said disk, a pivoted detent-bar provided with a tooth on its forward end, a dog pivoted at the rear end of said detent-bar, said tooth and dog adapted to project respectively in the path of said lugs, and means normally exerting upward pressure on said detent-bar.

110

6. The combination with a winding-drum, disk, actuating means and automatic interlocking means therefor, of non-alined lugs carried by said disk, a pivoted detent-bar provided

115

120

125

130

with a tooth on its forward end, a dog pivoted at the rear end of said detent-bar and a stop therefor, said tooth and dog adapted to project respectively in the path of said lugs, and 5 means normally exerting upward pressure on said detent-bar.

7. The combination with a winding-drum, disk, actuating means and automatic locking means therefor, of non-aligned lugs carried by 10 said disk, a pivoted detent-bar provided with a tooth on its forward end, a spring-operated dog pivoted on the rear end of said detent-bar and a stop therefor, said tooth and dog adapted to project respectively in the path of said 15 lugs, and means normally exerting upward pressure on said detent-bar.

8. The combination with a winding-drum, disk, actuating means and automatic locking means therefor, of non-aligned lugs carried by 20 said disk, a pivoted detent-bar capable of longitudinal and vertical movement, a tooth on the forward end of said detent-bar, a pivoted dog and stop therefor at the rear end of said 25 detent-bar, said tooth and dog adapted to project respectively in the path of said lugs, and means normally exerting upward pressure on said detent-bar.

9. The combination with a winding-drum, disk, actuating means and automatic interlocking means therefor, of non-aligned lugs 30 mounted on the peripheral edge of said disk, said lugs being curved on their upper face and tapering toward each other, forming opposed abutment-faces, a slotted detent-bar, a pivot-35 pin supporting said detent-bar within said slot, a tooth on the forward end of said detent-bar, a pivoted dog at the rear end of said 40 detent-bar, said tooth and dog adapted to project respectively in the path of one of said lugs, and means normally exerting upward pressure on the forward end of said detent-bar.

10. The combination with the winding-drum, disk, actuating means and automatic 45 interlocking means therefor, of non-aligned lugs mounted on the peripheral edge of said disk, a pivoted detent-bar provided with forward and rear projections adapted to ride over said lugs in one direction of rotation of 50 said disk and to engage same in the opposite direction of rotation, and means normally exerting upward pressure on the detent-bar.

11. The combination with the winding-drum, disk, actuating means and automatic 55 interlocking means therefor, of non-aligned lugs formed integral with the periphery of said disk, a pivoted detent-bar provided with forward and rear projections adapted to ride over said lugs in one direction of rotation of 60 said disk and to engage same in the opposite direction of rotation, and means normally exerting upward pressure on the detent-bar.

12. The combination with the winding-drum, disk, actuating means and automatic 65 interlocking means therefor, of non-aligned

lugs mounted on the peripheral edge of said disk, said lugs being curved and tapering rearwardly and forming opposed abutment-faces, a pivoted detent-bar provided with forward and rear projections adapted to ride over said 70 lugs in one direction of rotation of said disk and to engage same in the opposite direction of rotation, and means exerting upward pressure on the detent-bar.

13. The combination with a winding-drum, 75 disk, actuating means and automatic interlocking means therefor, of non-aligned lugs mounted on the peripheral edge of said disk, a pivoted detent-bar provided with a tooth on its forward end, a dog pivoted at the rear end 80 of said detent-bar, said tooth and dog adapted to project respectively in the path of said lugs, and means normally exerting upward pressure on said detent-bar.

14. The combination with a winding-drum, 85 disk, actuating means and automatic interlocking means therefor, of non-aligned lugs mounted on the peripheral edge of said disk, said lugs being curved and tapering toward each other forming opposed abutment-faces, 90 a pivoted detent-bar provided with a tooth on its forward end, a dog pivoted at the rear end of said detent-bar and a stop therefor, said tooth and dog adapted to project respectively in the path of said lugs, and means normally exerting upward pressure on said detent-bar.

15. The combination with the winding-drum, disk, actuating means and automatic interlocking means therefor, of a detent-bar 100 capable of vertical and longitudinal play, a resiliently-mounted buffer-block disposed adjacent the forward end of said detent-bar, means carried by said disk normally engaging said detent-bar, means normally exerting upward pressure on said detent-bar for operating 105 same vertically, and co-operating means between said disk and detent-bar for depressing said detent-bar and bodily shifting the same longitudinally beneath said resilient buffer-block.

16. The combination with a winding-drum, disk, actuating means and automatic interlocking means therefor, of non-aligned lugs carried by said disk, a detent-bar capable of vertical and longitudinal play, a tooth formed 115 on the forward end of said detent-bar, a dog pivoted at the rear end of said detent-bar, said tooth and dog being arranged in alignment with said lugs respectively and adapted to ride over in one direction of rotation of 120 the disk and to engage therewith in the opposite direction of rotation, means normally tending to operate said detent-bar vertically, and a resiliently-mounted buffer-block disposed adjacent the forward end of said detent-bar.

17. The combination with a winding-drum, disk, actuating means and automatic interlocking means therefor, of non-aligned lugs carried by said disk, a detent-bar capable of 130

vertical and longitudinal play, a tooth formed on the forward end of said detent-bar, a spring-controlled dog pivoted at the rear end of said detent-bar and a stop therefor, said tooth and 5 dog being arranged in alinement with said lugs respectively and adapted to ride thereover in one direction of rotation of the disk and to engage therewith in the opposite direction of rotation, means normally tending to operate said detent-bar vertically, and a resiliently-mounted buffer-block disposed adjacent the forward end of said detent-bar.

18. The combination with a winding-drum, disk, actuating means and automatic interlocking means therefor, of non-aligned lugs having opposed abutment-faces carried by said disk, a detent-bar capable of longitudinal and vertical play, a tooth on the forward end of said detent-bar coöoperating with one of 15 said lugs on said disk, a pivoted dog carried at the rear end of said detent-bar coöperating with the other of said lugs on said disk, a spring extending longitudinally above said detent-bar, a buffer-block carried by said 20 spring and normally supported adjacent the upper forward end of said detent-bar, and means exerting upward pressure on the forward end of said detent-bar.

19. The combination with a winding-drum, 30 disk, actuating means and automatic interlocking means therefor, of non-aligned lugs mounted on the periphery of said disk and having opposed abutment-faces, a slotted detent-bar, a headed pivot-pin supporting said detent-bar, 35 within said slot, allowing vertical and longitudinal play of said detent-bar, a friction-washer interposed between said headed pin and said detent-bar for partially retarding the latter's longitudinal movement, a tooth formed 40 at the forward end of said detent-bar coöperating with one of said lugs on said disk, a spring-controlled pivoted dog and stop therefor at the other end of said detent-bar coöperating with the other of said lugs, a spring 45 extending longitudinally above said detent-bar, a support for the forward end of said spring, a buffer-block carried by said spring adjacent the forward end of said detent-bar, and means exerting upward pressure on the 50 forward end of said detent-bar.

20. The combination with the winding-drum, disk, actuating means and automatic interlocking means therefor, of a slotted detent-bar, a pivot-pin supporting said detent-bar 55 within said slot, allowing vertical and longitudinal play of said detent-bar, resiliently-mounted means engaging and pressing against said detent-bar for partially retarding the latter's longitudinal movement, coöperating interlocking means carried by said disk and detent-bar, and means normally exerting upward pressure on said detent-bar.

21. The combination with a winding-drum, disk, actuating means and automatic interlocking means therefor, of a slotted detent-bar, a

pivot-pin supporting said detent-bar within said slot, allowing vertical and longitudinal play of said detent-bar, a spring-pressed washer on said pivot-pin engaging said detent-bar for partially retarding the latter's longitudinal movement, coöperating interlocking means carried by said disk and detent-bar, and means normally exerting upward pressure on said detent-bar. 70

22. The combination with the winding-drum, disk, actuating means and automatic interlocking means therefor, of a pivoted detent-bar and interlocking means between said detent-bar and disk, and adjustable means for holding said detent-bar in its locked position 80 with reference to said disk.

23. The combination with the winding-drum, disk, actuating means and automatic interlocking means therefor, of a pivoted detent-bar and interlocking means between said detent-bar and disk, and adjustable means for holding said detent-bar in its locked position 85 with reference to said disk, comprising a spring normally tending to press against said detent-bar and operating means for withdrawing said 90 spring from engagement with said detent-bar.

24. The combination with the winding-drum, disk, actuating means and automatic locking means therefor, of a pivoted detent-bar and interlocking means between said detent-bar and disk, and adjustable means for holding said detent-bar in its locked position 95 with reference to said disk, comprising a spring adapted to press against said detent-bar, and means for withdrawing said spring out of engagement therewith, comprising a spindle having a shank portion projecting transversely beneath said spring, and means for rotating said spindle. 100

25. The combination with a winding-drum, 105 disk, actuating means and automatic locking means therefor, of non-aligned lugs carried by said disk, a pivoted detent-bar capable of vertical and longitudinal play, a tooth formed at the forward end of said detent-bar coöperating with one of said lugs, a pivoted dog at the rear end of said detent-bar coöperating with the other of said lugs, means exerting upward pressure on the forward end of said detent-bar, a resiliently-mounted buffer-block disposed adjacent the upper forward end of said detent-bar, a spring having a bent end normally resting beneath said buffer-block and tensioned to spring downwardly into engagement with said detent-bar, and means for controlling the movement of said spring. 110 115

26. The combination with a winding-drum, disk, actuating means and automatic interlocking means therefor, of non-aligned lugs carried by said disk, a pivoted detent-bar capable of 120 vertical and longitudinal play, a tooth formed at the forward end of said detent-bar coöperating with one of said lugs, a pivoted dog at the rear end of said detent-bar coöperating with the other of said lugs, means exerting 125 130

upward pressure on the forward end of said
detent-bar, a resiliently-mounted buffer-block
disposed adjacent the upper forward end of
said detent-bar, a spring having a bent end
5 normally resting beneath said buffer-block
and tensioned to spring downwardly into en-
gagement with said detent-bar, and means for
controlling the movement of said spring, com-
prising a suitably-supported spindle provided
10 with a projecting shank extending trans-
versely beneath said spring and an index-fin-
ger for rotating said spindle.

27. The combination with a slotted casing,
of a winding-drum, disk, actuating means and
15 interlocking means therefor, inclosed within
said casing, a housing on said casing above said
slot, a detent-bar pivotally mounted in said
housing above said slot and capable of verti-
cal and longitudinal play, non-aligned lugs car-
20 ried by the periphery of said disk and adapted
to operate adjacent said slot, a tooth on the
forward end of said detent-bar coöperating
with one of said lugs, a pivoted dog carried
at the rear end of said detent-bar coöperating
25 with the other of said lugs, a resiliently-mount-
ed buffer-block adjacent the upper forward
end of said detent-bar, and means exerting
upward pressure on the forward end of said
detent-bar.

30. 28. In portable trolley-retrieving mech-
anism, the combination with a frame adapted to
be carried on the front and rear of a car, said

frame provided at its base with an aperture
and at its upper end with a recessed portion
and a recessed pivoted locking-button coöp- 35
erating with said recessed portion of said
frame, of a portable casing provided on its
underneath and top faces with lugs adapted
to register with said aperture and recesses, and
internal mechanism coöperating together for 40
normally holding the trolley-rope taut and
mechanically retrieving the trolley-pole upon
the sudden upward movement of the latter.

29. In portable trolley-retrieving mech- 45
anism, the combination with an oval frame
adapted to be carried on the front and rear of
a car, said frame provided at its base with an
aperture and at its upper end with a recessed
portion and a recessed pivoted locking-button 50
coöperating with said recessed portion of said
frame, of a cylindrical casing provided on its
underneath and top faces with lugs adapted
to register with said aperture and recesses, and
internal mechanism coöperating together for 55
normally holding the trolley-rope taut and
mechanically retrieving the trolley-pole upon
the sudden upward movement of the latter.

In testimony whereof we affix our signatures
in presence of two witnesses.
